METHOD OF AND MECHANISM FOR REGISTERING SHEETS

Edwin W. Goodwin, New Rochelle, N. Y., assignor to Dexter Folder Company, New York, N. Y., a corporation of New York

Application February 6, 1936, Serial No. 62,706
Renewed November 2, 1938

20 Claims. (Cl. 271—58)

This invention relates to a method of and mechanism for registering sheets and while capable of general use, is more particularly adapted for use in registering sheets with printing or other machines as the sheets are being fed automatically thereto by suitable means for this purpose.

One object of the present invention is to provide an improved method of and mechanism for registering large or heavy sheets of cardboard, tin, or other similar materials.

Another object of the present invention is to provide a method of and mechanism for registering sheets which, through pulling and pushing forces simultaneously applied thereon at opposite edge portions thereof, enables large or heavy sheets to be more readily and accurately registered.

Another object of the present invention is to provide a method of and mechanism for registering sheets, which prevents buckling of the sheets while at the same time enabling pulling and pushing forces to be applied on opposite edge portions of said sheets to register same.

Another object of the present invention is to provide an improved method of and mechanism for side registering sheets with respect to a machine to which the sheets are fed.

Another object of the present invention is to provide duplicate sheet registering mechanisms which act on opposite edge portions of the sheets simultaneously and which are reversible to move sheets in one direction or in a direction opposite thereto, as desired.

Another object of the present invention is to provide duplicate side registering mechanisms either or both of which may be used as desired to move the sheets laterally of a machine in one direction or in the opposite direction to side register the sheets with said machine.

Another object of the present invention is to provide side registering mechanism which enables any sheet having a rough or ragged side registering edge to be accurately side registered without danger of displacement of the sheet from the proper position of registry therefor.

Another object of the present invention is to provide side registering mechanism which prevents the side registering edge of any sheet from riding up on the registering face of the side registering means.

These and other objects of the present invention will appear as the following description thereof proceeds and in order to more clearly understand said invention reference may be had to the accompanying drawings which illustrate

one mechanical embodiment of the inventive idea.

In said drawings:

Fig. 1 is a side elevation of the front end of a sheet feeder looking from the left of Fig. 3 and showing sheet registering devices embodying the present invention;

Fig. 2 is a view similar to Fig. 1, looking from the right of Fig. 3;

Fig. 3 is a transverse vertical sectional view taken on the line 3—3 of Figs. 1 and 2 and showing a pair of sheet registering devices constructed and mounted in accordance with the present invention;

Fig. 4 is a top plan view of one of the sheet registering devices shown in Fig. 3;

Fig. 5 is a vertical longitudinal sectional view taken on the line 5—5 of Fig. 4;

Fig. 6 is a transverse vertical sectional view taken on the line 6—6 of Fig. 4; and

Fig. 7 is an end view similar to Fig. 3 and illustrating diagrammatically the operation of said side registering devices.

Referring to the drawings, wherein like reference characters designate like parts throughout the several views, 5 indicates a feed board extending forwardly and downwardly from a sheet feeder proper (not shown) and provided with brackets 6 and 7 which are bolted or otherwise suitably secured to right and left hand frames 8 and 9, respectively at the front end of said feed board (Figs. 1 and 2). The frames 8 and 9 may, if desired, be bolted or otherwise suitably secured to the frames 10 and 11 of a printing press or other machine to which the sheets are fed.

Extending forwardly from the sheet feeder proper and over the feed board 5 thereof are driven tapes 12 the front ends of which pass around a roller 13 that is journaled in suitable bearings on the frames 8 and 9. These frames 8 and 9 support the front end mechanism including side registering devices to be hereinafter described in detail. Frames 8 and 9 may, if desired, be connected with the side frames of the sheet feeder proper, as by tie bars 14 the forward ends of which are bolted or otherwise suitably secured to the frames 8 and 9.

The front end frames 8 and 9 are provided with upwardly and rearwardly directed extensions 15 and 16 connected together at their rear ends by a supporting shaft 17 having secured thereto, as by thumb screws 18, a plurality of brackets 19. These brackets 19 have bolted or otherwise suitably secured thereto a plurality of top rods 20.

extending longitudinally of the feed board 5 above the driven tapes 12 and serving to prevent displacement of the sheets 25 therefrom. The front end frames 8 and 9 are connected together by 5 tie rods 21, 22, 23 and 24, the tie rods 21 and 22 passing through suitable openings in the extensions 15 and 16, and the tie rods 23 and 24 passing through suitable openings in the front end frames 8 and 9.

10 In accordance with the present invention each of the sheets 25 fed by the driven tapes 12 or other suitable means is, prior to delivery thereof to the printing press or other machine, side registered therewith both pulling and pushing the 15 sheet laterally of said press or machine. For this purpose, two sets of side registering devices, indicated broadly at 26 and 27, are employed. These devices are preferably mounted in spaced relation on the front end of the feed board and 20 may, if desired, be operated from the sheet feeder. As herein shown, however, said devices are operated from the press or other machine as follows.

Extending upwardly and rearwardly from said 25 press or machine and driven in any suitable manner thereby, is a jack shaft 28 the upper end of which is journalled in a suitable bearing provided by a bracket 29 that is bolted or otherwise suitably secured to the front end frame 8 (Figs. 1 30 and 3). This jack shaft 28 has fixed on the upper end thereof a bevel pinion 30 which meshes with a bevel gear 31 that is fixed on a cam shaft 32 extending transversely of the front end mechanism and journalled in suitable bearings in the 35 front end frames 8 and 9. The cam shaft 32 also has fixed thereon a spur gear 33 which meshes with a similar gear 34 journalled in any suitable manner on a bracket 35 that is bolted or otherwise suitably secured to the front end 40 frame 8.

The spur gear 34 meshes with a similar gear 36 journalled in any suitable manner on the bracket 35. This spur gear 36 meshes with a similar gear 37 that is fixed on one end of a 45 shaft 38 for driving rotatable parts of the side registering devices 26 and 27 hereinafter referred to. This shaft 38 is journalled in suitable bearings in the front end frames 8 and 9 and also in a center bracket 39 that is bolted or otherwise suitably secured to the tie bars 23, 50 24 and provides a bearing for the cam shaft 32.

It will thus appear that the shaft 38 is rotated to drive said rotatable parts of the side registering devices through the described driving connections for said shaft with the jack shaft 28. The side registering devices 26, 27 are identical in construction and operation and a description of one of said side registering devices will therefore be sufficient for both of the same. Each of 60 these side registering devices is properly operated, mounted, and constructed as follows.

The driven shaft 38 above referred to is provided longitudinally thereof with a keyway 40. Fixed on and slidable along the shaft 38, as by 65 a key 41 in keyway 40, is a spiral gear 42 that is enclosed in a housing indicated broadly at 43. This housing 43 is comprised by a cored block 44 slidably mounted on the shaft 38, and side plates 45, 46 bolted or otherwise suitably secured 70 to said block and slidably mounted on the tie rods 23, 24. It will thus appear that the spiral gear 42, the housing 43, and all parts carried by said housing may be adjusted laterally of the front end mechanism in accordance with variations 75 in width of the sheets to be registered,

and without disturbing the driving connections for shaft 38 with spiral gear 42 and the following described parts on said housing driven thereby.

The spiral gear 42 meshes with a similar gear 47 housed in the cored block 44 and fixed on a stud shaft 48 that is journalled in suitable bearings in said block. This stud shaft 48 has one end projecting rearwardly from the block and journalled in a plate 49 bolted to said block and spaced at the upper end therefrom. Fixed on the stud shaft 48 between the block 44 and the plate 49 is a side registering wheel which forms the lower driven part of the side registering device. This wheel 50 is provided circumferentially and at the rear thereof with a beveled edge 51 enabling the sheets to more readily pass over the wheel prior to the side registering operation. The block 44 and the side plates 45, 46 have bolted or otherwise suitably secured thereto a plate 52 provided with a suitable opening through which the upper part of the wheel 50 extends. This plate 52 is also provided with a suitable recess for the upper part of the spiral gear 47.

The side plate 46 of the mechanism 27 has bolted or otherwise suitably secured thereto a 25 bracket 53, the side plate 45 of the mechanism 26 having bolted or otherwise suitably secured thereto a similar bracket 53. This difference in mounting of the bracket 53 on the two mechanisms 26, 27 is occasioned by the need of having the bracket 53 outside of the side edges of the sheet.

Cooperating with the lower side registering wheel 50 and vertically movable toward and away from the same is an upper registering or gripping 35 wheel 54. This wheel 54 is journalled, as by an anti-friction bearing 55 and a stud 56, in the bifurcated end 57 of an arm 58. This arm 58 is fixed on the reduced upper end 59 of a plunger 60, as by a lock nut 61 threaded on said upper 40 end of said plunger. The upper wheel 54 projects downwardly through a suitable opening in a plate 62 for cooperation with the lower driven registering wheel 50. This plate 62 is provided around the inner side and ends thereof with a flared 45 edge 63, as clearly shown in Figs. 4 and 5 of the drawing, in order to enable the sheets to pass freely between said plate and the plate 52. The plate 62 is bolted or otherwise suitably secured to the bifurcated end 57 of arm 58, the bolts or 50 fastening means 64 (Fig. 3) passing through ears 65 secured to or formed integrally with said plate.

Plate 62 is provided on the outer or registering side thereof with slots 66 within which extend a side registering block or abutment 67 that is 55 provided with a slot 68 into which extends a tongue 69 formed on plate 62 between the slots 66. The side registering block or abutment 67 is bolted or otherwise suitably secured, as at 70, to the arm 58 in a slot 71 at the bottom thereof. The lower plate 52 is provided with slots and a tongue similar to the slots 66 and tongue 69, in order to receive and guide the side registering block or abutment 67 during downward movement of the same with the arm 58.

The plunger 60 is mounted for reciprocating movement in a suitable opening in the bracket 53. Turning movement of said plunger and the arm 58 such as would displace the upper wheel 54 from a position immediately above the lower 70 wheel 50, is prevented by gib 72. These gib 72 bear against opposite flat sides of the arm 58 and are interposed between said arm and flat extensions 73 on the upper end of the bracket 53. Screws 74 threaded in the extensions 73 and 75

bearing against the gibs 72 in suitable recesses therein serve to maintain the arm 58 and wheel 54 in proper position. These screws 74 also may be employed to adjust said gibs and compensate for wear on said arm incident to its vertical reciprocating motion.

Secured on the lower end of the plunger 60, as by a set screw 75, is a pin 76 on which is journaled a roller 77 located between the plunger 10 and an annular shoulder 78 of said pin. Outwardly beyond said shoulder the pin 76 is reduced and extends through a suitable opening in the lower end of a spring pressed rod 79 that is retained against displacement from the pin by a 15 cotter pin or any suitable means for this purpose. The spring for rod 79 is indicated at 80 and extends therealong between a collar 81 secured on said rod and a tubular adjusting screw 82 in which the upper end of the rod extends. This 20 screw 82 is threaded in a suitable opening of an extension 83 formed on the upper end of bracket 53. Screw 82 is provided with a suitable adjusting head 84 and a lock nut 85.

Reciprocating motion of the plungers 60 and 25 the upper wheels 54 is imparted thereto by oscillating bars 86 (Fig. 3) and the spring pressed rods 79. Each bar 86 is bolted or otherwise suitably secured on arms 87 that are fixed in any suitable manner on a rock shaft 88 which extends 30 transversely of the front end mechanism and is journaled in suitable bearings in the front end frames 8 and 9 and the center bracket 39.

The arms 87 are cam operated in one direction and spring operated in the opposite direction to 35 oscillate the bars 86. For this purpose, the rock shaft 88 has fixed thereon a cam lever 89 one arm 90 of which has journalled thereon in any suitable manner a roller 91 which engages a cam 92 that is fixed on the cam shaft 32. Another arm 93 on said cam lever is provided with a pin 94 which extends through the lower apertured ends of a spring pressed rod 95 retained against displacement from said pin by a cotter pin or any suitable means for this purpose. The spring 96 for rod 95 extends over said rod between a collar 97 fixed thereon and a pin 98. The upper end of rod 95 extends through a suitable opening in pin 98 and said pin is secured in any suitable manner on the center bracket 39. It will thus appear that during rotation of cam shaft 32 the rock shaft 88 will, by the cam lever 89 and spring rod 95, be rocked and likewise rock the arms 87 and the bars 86. The bars 86, together with the spring rods 79 will, in turn, reciprocate the plungers 60 so that the upper wheels 54 are moved vertically toward and away from the lower driven registering wheels 50.

Referring to Fig. 3 of the drawings, it will be noted that each bar 86 is of substantial length. This is to enable the plunger 60 of the side registering devices 26, 27 to be reciprocated regardless of variations in the position of said devices effected in accordance with variations in width of the sheets to be registered. Adjustment of the side registering devices in accordance with variations in width of the sheets is preferably effected through the medium of a clamping and adjusting handle 99 for each of said devices. The handle 99 is provided on the upper end of a shaft 100 the lower end 101 of which is rounded and threaded and extends through suitable openings in a split clamp 102 mounted on the stay shaft 23. The lower rounded end of shaft 100 is threaded in a part of clamp 102 and said clamp has threaded therethrough a pin 103 provided thereon at op-

posite sides of the clamp with adjusting and locking nuts 104.

The inner end of pin 103 has secured thereto, as at 105, a stud 106 which is secured, as at 107, to one of the extensions 73 of the bracket 53 5 that is secured to the housing 43. It will thus appear that each side registering device may be clamped in the desired position of adjustment on the stay shaft 23 by the handle 99 and clamp 102, and that by loosening the clamp, shifting its 10 corresponding side registering device, and again tightening the clamp, each side registering device may be independently adjusted laterally of the front end mechanism as desired. Further, a fine or micrometer adjustment of each side registering device may be made after an initial adjustment thereof, by the adjusting and locking nuts 104 and pin 103.

The operation of the side registering devices will be readily understood from the foregoing and 20 may be briefly summarized as follows. Assuming that the sheets are to be side registered to the left, as viewed in Figs. 3 and 7, the parts will be positioned as shown in full lines therein with the side registering devices 26, 27 adjusted by 25 the described means for this purpose and spaced apart so that when the upper wheels 54 descend and the sheet is initially gripped between said wheels and the lower wheels 50 the distance A (Fig. 7) from the left hand edge of the sheet to 30 the adjacent registering block or abutment 67 is greater than the distance B between the right hand edge of the sheet and a vertical line C on the centers of the adjacent wheels 50, 54. The right hand edge of the sheet 25 will therefore, during its lateral movement effected by 35 wheels 50, 54, pass out of the bite of the right hand registering wheels 50, 54 before the left hand edge of the sheet strikes the left hand registering block or abutment 67. The side registering devices having been adjusted as aforesaid, the sheet feeder operates to feed the sheets one after another over the feed board 5 to the driven conveyor tapes 12 which carry the sheets forward to the side registering devices. The side registering devices are operated in timed relation with the sheet feeder and the printing press or other machine to be fed and before each sheet reaches 40 said devices the arms 58 and parts carried thereby are raised by the described means for this 45 purpose, enabling the sheet, as it is being fed forwardly by tapes 12, to pass over the lower registering wheels 50 between plates 52 and 62. The front end of the sheet also passes over supporting tongues 105' and 106'. The tongues 105' 50 are secured in any suitable manner on blocks 107' that are bolted or otherwise suitably secured on the housings 43 at the fronts and tops thereof. The tongues 106' are mounted in any suitable 55 manner on the tie bar 23. After the sheet has 60 been fed between plates 52, 62 and over wheel 50 and tongues 105', 106', said sheet is then stopped, as by engagement of its front end with drop guides (not shown), whereupon the arms 58 are lowered by the described means for this purpose 65 and the sheet is gripped between the upper and lower wheels 50, 54 of devices 26, 27.

Wheels 50 of both of these devices are driven in the same direction so that the sheet is pulled by the wheels 50, 54 of the left hand device 26 70 and pushed by the wheels 50, 54 of the right hand device 27. These two devices being set as above described, the right hand edge of the sheet will pass out of the bite of the adjacent wheels 50, 54 before the left hand edge of the sheet is pulled 75

laterally by the adjacent wheels 50, 54 against the left hand abutment 67. This prevents buckling of the sheet during the side registering operation. The sheet having been pulled laterally into engagement with the left hand abutment 67 is now properly side registered, whereupon the arms 58 of both devices 26, 27 are raised by the described means for this purpose, the aforesaid drop guides of the press are likewise raised, and the sheet is taken by the press or other machine for operation thereon in the usual manner.

In the event the sheets are to be side registered to the right, as viewed in Figs. 3 and 7, of the drawings, the lower registering wheels 50 are both rotated in a direction opposite to that in which they are rotated when the sheet is side registered to the left. For this purpose, the driven shaft 38 is arranged for sliding as well as rotary movement in its bearings so that upon movement of said shaft to the left, the gear 37 will mesh with a gear 108. This gear 108 is journaled in any suitable manner on the bracket 35, and secured to said gear or compounded therewith in any suitable manner is a similar gear 109. This gear 109 meshes with a gear 110 that is compounded with or secured in any suitable manner to the gear 36. Through the compound gears aforesaid, the wheels 50 of side registering devices 26, 27 may, when gears 37, 108 are in mesh, be rotated to pull and push the sheet to the right, Figs. 3 and 7, instead of to the left as previously described. The operation is otherwise the same as first described except that in registering the sheet to the right, the two side registering devices 26, 27 are set so that the left hand edge of the sheet passes out of the bite of the left hand wheels 50, 54 before the right hand edge of the sheet is pulled laterally by the adjacent wheels 50, 54 into engagement with the right hand side registering block or abutment 67.

In order to shift the shaft 38 to operate the side registering devices 26, 27 for right or left hand registering as above described, said shaft is provided on one end thereof with an operating knob or handle 111. In the full line position of the parts shown in Fig. 3, wherein the sheets are registered to the left, the shaft 38 is locked by a latch 112 that is engaged over the shaft between frame 9 and a collar 113 of the knob or handle 111. The latch may, if desired, be engaged with a pin 114 secured in and projecting outwardly from frame 9. When the sheets are to be registered to the left, Figs. 3 and 7, the latch 112 is raised and the shaft 38 is shifted to the left as before described, whereupon said shaft may be locked by engaging the latch 112 over the reduced portion 115 of handle or knob 111 between the latter and the collar 113.

Side registering mechanism embodying the present invention is particularly adapted for large sheets and sheets of heavy material such as tin, cardboard or the like, the side registering of which heretofore has sometimes been difficult because of the size and weight of such sheets. Side registering mechanism embodying the present invention may, however, be employed with smaller and lighter sheets and further, either of the side registering devices 26, 27 may be employed without the other for this purpose. In this case, the side registering device which will not be employed, is thrown out of operation by locking the arm 58 in raised position. This is accomplished by a latch 116 pivoted on a stud 117 carried by one of the extensions 73 of bracket 53. This latch 116 is adapted to be engaged with and

disengaged from a reduced part 118 formed on plunger 60 below a head 119 thereon. The manner of locking the plunger 60 and arm 58 in raised position is illustrated in Fig. 5 by the dotted line showing therein of latch 116 and head 119.

It will be noted that the side registering abutment or block 67 is mounted on the arm 58 and raised and lowered therewith. This is a decided advantage in the feeding and registering of sheets having ragged or uneven edges because in such cases, the registering block is raised up out of the way when the sheet is fed to the side registering device and also when it is fed therefrom to the press or other machine to be fed, so that interference of the block with the sheet is prevented and perfect registry of the sheet is obtained and maintained regardless of the formation of the registering edge of the sheet.

It will further be noted that the tongue 89 on the upper registering plate 82 prevents the edge of the sheet from riding up on the inner or registering face of the block or abutment 67. This is a decided advantage in the operation of side registering thin stock or curled stock, the edges of which might, in some cases, ride up on said block as aforesaid, with resulting imperfect or improper registry of the sheets.

It will also be noted that the springs 80 of rods 79 not only act to move arms 58 and upper wheels 54 downwardly but also act to maintain the sheet gripped between said wheels and lower wheels 50 until said arms are raised by bars 86. Further, the degree of gripping action of wheels 50, 54 on the sheet may be regulated or adjusted as desired by turning screws 82 in one direction or the other to increase or decrease the tension of springs 80.

While one embodiment of the present invention is herein illustrated and described with more or less particularity, it is to be expressly understood that said invention is not limited to said embodiment or otherwise than by the terms of the appended claims.

Having thus described my invention which I claim is:

1. In a sheet registering mechanism, means acting on a side portion of a sheet to pull it laterally of a machine into a position of side registry therewith, means acting on an opposite side portion of the sheet to grip and push it laterally of said machine toward said position, and devices for adjusting and spacing said means relatively so that the sheet is released by its pushing means as said sheet is about to be pulled into said position by said pulling means.

2. The method of side registering a sheet, which comprises pulling on one side portion of the sheet and moving it laterally into a position of side registry therefor, gripping and pushing on an opposite side portion of the sheet while it is being pulled and moved laterally as aforesaid, and terminating the gripping and pushing action on said sheet as it is about to be moved into said position.

3. In a sheet registering mechanism, means for selectively moving a sheet in one direction or another to register it, and devices forming part of said means and acting to grip and pull on one edge portion of the sheet and grip and push on an opposite edge portion thereof in either direction of movement of the sheet aforesaid.

4. In a sheet registering mechanism, means for selectively moving a sheet laterally of a machine in one direction or another to side register the sheet therewith, and devices forming part of said means and acting to grip and pull on one side

portion of the sheet and grip and push on an opposite side portion thereof in either direction of movement of the sheet aforesaid.

5. In a sheet registering mechanism, means for pulling a sheet in one direction, means for pushing the sheet in that direction, and mechanism for reversing the operation of both said means without displacement thereof so that a sheet may be pulled and pushed thereby in the 10 opposite direction.

6. In mechanism of the character described, a side registering device, rotary means for moving a sheet laterally into engagement therewith, and means for raising said device above the 15 sheet after engagement of said sheet therewith.

7. In mechanism of the character described, a side registering device, means for raising it before a sheet is fed past the same, means for there- 20 after lowering the side registering device, and rotary means for moving the sheet laterally into engagement with said device when it has been lowered.

8. In mechanism of the character described, a side registering device, means for lowering the 25 same, rotary means for moving a sheet laterally into engagement with the device when it has been lowered, and means for raising the device before the sheet is fed past the same to said sheet moving means and after said sheet has been en- 30 gaged thereby with said device.

9. In a sheet registering mechanism, a lower rotary sheet moving member, an upper rotatable sheet engaging member movable toward and away from said lower member, and a sheet registering device or abutment mounted on said upper member and movable thereby into and out of the plane of the sheet.

10. In a sheet registering mechanism, opposed 40 rotary sheet gripping and moving members, means for moving one member toward and away from the other, and a sheet registering device or abutment mounted on a part of said means and movable thereby into and out of the plane of the sheet.

45 11. In a sheet registering mechanism, a sheet registering device, means for moving a sheet into engagement therewith, a plate adjacent the sheet registering device and under which the sheet is moved thereto by said means, means intercon- 50 necting the plate and the sheet registering device for preventing the registering edge of the sheet from riding up on the registering face of said device, and means for actuating the plate and the sheet registering device and moving the latter into and out of operative position.

55 12. In a sheet registering mechanism, an os- cillating bar, a support parallel therewith, a car- riage or housing mounted on the support and movable longitudinally of the latter and the bar to various positions of adjustment, a plunger slid- ably mounted on the carriage or housing and actuated vertically in one direction by the os- cillating bar in any position of adjustment of said carriage or housing longitudinally of said bar, 60 spring means interposed between the carriage or housing and said plunger for actuating the latter vertically in the opposite direction, and a sheet engaging member mounted on the plunger and reciprocated thereby.

70 13. In a sheet registering mechanism, sheet moving and gripping means comprising a pair of spaced sheet moving wheels and a pair of

spaced sheet grippers cooperating with the wheels and movable toward and away from the same, and means for selectively driving both of said wheels in one direction or in a direction opposite thereto.

5 14. In a sheet registering mechanism, sheet moving wheels arranged in spaced relation, means for driving both wheels in one direction to move a sheet toward one side of a machine to which it is fed, and means for driving both wheels in the 10 opposite direction to move a sheet toward the opposite side of said machine.

15 15. In a sheet registering mechanism, spaced sheet moving wheels, means for selectively driv- 15 ing both of said wheels in one direction or in a di- rection opposite thereto and including shiftable gear means, and means for shifting said shiftable gear means.

16. In a sheet registering mechanism, spaced sheet moving wheels, means for selectively driv- 20 ing both of said wheels in one direction or in a di- rection opposite thereto and including shiftable gear means, means movable to different posi- 25 tions for shifting said gear means, and means for locking said shifting means in each of said posi- tions.

17. In a sheet registering mechanism, means for acting on one side edge portion of a sheet and provided with opposed movable gripping surfaces that engage the sheet at the top and bottom 30 thereof adjacent said side edge portion and pull the sheet into a position of side registry therefor, and means for acting on an opposite side edge portion of the sheet and provided with opposed movable gripping surfaces that engage the sheet 35 at the top and bottom thereof adjacent said last named side edge portion and push said sheet to- ward said position during sheet gripping and pulling action of said first named means.

18. The method of registering a sheet, which 40 comprises imparting movable gripping action on the top and bottom surfaces of the sheet adjacent one side edge thereof and pulling the sheet into a position of side registry therefor, and im- parting movable gripping action on the top and 45 bottom surfaces of the sheet adjacent the oppo- site side edge thereof and pushing said sheet to- ward said position.

19. In a sheet registering mechanism, means for acting on one side edge portion of a sheet and 50 including opposed movable gripping elements that engage the sheet at the top and bottom thereof adjacent said side edge portion and pull the sheet into a position of side registry therefor, and means for acting on an opposite side edge 55 portion of the sheet and for pushing the sheet to- ward said position during the sheet gripping and pulling action thereon, said last named means including a positively actuated element engaging a surface of the sheet adjacent said last named 60 edge portion thereof.

20. The method of side registering a sheet, which comprises movably applying gripping ac- 65 tion on top and bottom surfaces of the sheet ad- jacent one side edge portion thereof and pulling the sheet into a position of side registry there- for, and pushing the sheet toward said position by applying movable pushing action on a surface of the sheet adjacent an opposite side edge portion thereof.

70 EDWIN W. GOODWIN.
